UNITED STATES PATENT OFFICE

123,900

DESIGN FOR A CABINET FOR A GAME APPARATUS

Harry E. Williams and Lyndon A. Durant,
Chicago, Ill.

Application March 30, 1940, Serial No. 91,358

Term of patent 3½ years

To all whom it may concern:

Be it known that we, Harry E. Williams and Lyndon A. Durant, both citizens of the United States and both residents of Chicago, in the county of Cook and State of Illinois, have invented a new, original, and ornamental Design for a Cabinet for a Game Apparatus, of which the following is a specification, reference being had to the accompanying drawing, forming a part thereof, and in which:

Fig. 1 is a perspective view of a cabinet for a game apparatus embodying our new design; and
Fig. 2 is a front elevational view thereof on a slightly smaller scale.

We claim:

The ornamental design for a cabinet for a game apparatus, as shown.

HARRY E. WILLIAMS.
LYNDON A. DURANT.
